UNITED STATES PATENT OFFICE

2,509,004

POULTRY DRINKING FOUNTAIN

William L. Lipman, Vineland, N. J.

Application January 15, 1946, Serial No. 641,288

2 Claims. (Cl. 119—74)

1

The invention relates to a new and useful poultry drinking fountain, and while its use is not limited to any particular type or size of poultry it is especially appropriate for providing a source of water supply for a flock of turkeys.

An object of the invention is to provide an exceedingly sturdy poultry drinking fountain comprising a metal funnel, preferably cast iron, to be mounted on a suitable drain pipe, either metal or terra cotta, of desirable diameter and of appropriate length or height; and a metal drinking cup uniquely assembled within the body of the funnel to prevent water from "creeping" by conduction from the drinking cup to and over the body of the funnel.

Another object of the invention is to assemble the water supply fittings in a manner to assist in holding the drinking cup in place.

Another object of this invention is to so connect the water supply fittings that the fountain may be connected with a feed line located over head or under ground.

Another object of this invention is to connect a valve directly on the lead-in branch of the water supply conduit from the feed line to the nozzle whereby each fountain is individually controlled permitting any one or more of a group of fountains to be shut off when necessary or desired.

A further object of this invention is to so mount the nozzle in the fountain that said nozzle can be positioned upright for use as a bubbler or reversed to cause the water to flow directly into the cup. When the nozzle is inverted and the flow of water is sufficiently strong, the drinking cup practically becomes a self-cleaning one. Also when the nozzle is inverted it prevents the entrance of air into the lead-in branch if connected to a low pressure water source and water is drawn from the feed line ahead of the fountain.

A still further object of the invention is to provide an inexpensive but durable guard to prevent the poultry from roosting on the fountain, in combination with the other elements to assist in holding the drinking cup in place.

With the above and other objects in view this invention consists of the details of construction and combination of elements hereinafter set forth and then designated by the claims.

In order that those skilled in the art to which this invention appertains may understand how to make and use the same I will describe a construction in detail referring by numerals to the accompanying drawing forming a part hereof, in which:

2

Fig. 1 is a side elevation of the poultry drinking fountain mounted on a small drain pipe which, in turn is mounted in a larger or main drain pipe, and connected to a below surface water supply or feed pipe.

Fig. 2 is a top plan view thereof.

Fig. 3 is a vertical sectional view of the same, with some of the parts shown in elevation and the water supply pipes removed.

Fig. 4 is a bottom view of the funnel.

Fig. 5 is a side elevation of the drinking cup with a portion broken away to illustrate a detail of construction.

Fig. 6 is a side view of the funnel, on a reduced scale, on a larger sized drain pipe.

Fig. 7 is a similar view showing the funnel on an intermediate sized drain pipe.

Fig. 8 is an enlarged perspective view of the elbow of the nozzle unit.

Fig. 9 is an enlarged perspective view of the catch.

In carrying out my invention as herein embodied 10 represents the funnel, preferably of cast iron, including a bowl shaped body 11 diminishing into a restricted or reduced and tapered neck 12 which may fit into a small sized drain pipe 13. This drain pipe 13 may lead directly to or be a part of a drainage system or it may be mounted in a larger drain pipe 14 by use of an adapter 15.

As here shown, the larger drain pipe has a bell portion 16 in which the adapter 15 rests and said adapter includes a collar 17 and a flange 18 reinforced by ribs 19. The pipe 13 fits in the collar 17 and is temporarily held in any longitudinal adjustment by the set screw 20. In order to prevent the pipe 13 dropping into the pipe 14 should the set screw become loose, one or more sections of the pipe 13 are partially severed therefrom and said sections bent outward to form ears or stops 21.

On the under side or exterior of the bowl shaped body 11 of the funnel 10 are formed a number of arcuate ribs 22 and 22a arranged in a plurality of concentric circles to fit different sized drain pipes 14a and 14b as illustrated in Figs. 6 and 7, respectively. These ribs fit inside or outside of the pipe on which the fountain is mounted and prevents displacement or wobbling of the funnel relative to its pipe.

The upper edge of the funnel body 11 has several notches 23 formed therein, a radial hole 24 through one side and communicating with the space between a pair of spaced ears 25, one of which has a screw 26 threaded therethrough, and

an outwardly projecting lug 21 at the rim of said body and on which is pivoted a catch 28 for a purpose to be presently described. Said catch 28, Fig. 9, includes a circular body 28a through which a screw 28b passes and from which projects the nose 28c.

A drinking cup 29, smaller than the bowl shaped body of the funnel, is disposed centrally within said funnel body and has radial arms 30 projecting from the upper portion thereof with the outer ends extending upwardly, as at 31, and then horizontally to provide terminals 32 in a plane above the major or main portions of the arms. These arms, especially the terminals 32 thereof, set in the notches 23 and therefore support the drinking cup below the top of the funnel body. This will positively prevent any water in the drinking cup from "creeping" upwardly along the arms 30 and dripping over the edge of the funnel body.

An elbow fitting 33 has a threaded nipple 34 and is permanently connected to the nozzle pipe 35 which is projected through the hole 24 from the outside of the funnel body. This nozzle pipe 35 is of a length to reach approximately to the axis of the funnel or the center of the drinking cup and the inner end is threaded to receive the nozzle 36 which is screwed thereon subsequent to the nozzle pipe being put into place. Said nozzle pipe 35 rests in a notch 37 in the edge of the drinking cup, Fig. 5, provided for this purpose.

The elbow fitting 33 has flat sides and is of a width to fit the space between the ears 25 so that said fitting and, consequently, the nozzle pipe and nozzle cannot turn or rotate when the parts are in place. By screwing the screw 26 inward until it engages the elbow fitting, the parts are prevented from being accidentally withdrawn.

A water supply line 38, Fig. 1, is shown located underground or below the fountain and a lead-in branch 39 is connected thereto and the fountain. For purposes of illustration, said lead-in branch is depicted as including a reducing bushing 40 connected to a nipple 41 leading from the supply line, a shut-off valve 42, and a tube 43 connected to said valve 42 and the nipple 34 of the elbow fitting 33, thus connecting the supply line with the nozzle pipe and nozzle.

If the water supply line is overhead, the screw 26 is loosened, the elbow fitting is withdrawn from the space between the ears 25 and said elbow fitting reversed or inverted. The valve 42 will still be in the lead-in branch so that when closed there will be no pressure on the fountain.

A guard 44 includes a ring 45, preferably wire, and a plurality of wire rods 46 soldered or otherwise secured to a metal cap 47 and the outside of the ring 45 so that the guard is in the general form of a cone. The lower ends of the rods 46 extend below the ring and project inwardly at suitable angles to form fingers 48 which fit under the body 11 of the funnel 10. The inwardly projecting ends or fingers 48 at one side of the guard are placed under one side of the funnel body by tilting the guard. Next the guard is returned to its upright position and the opposite fingers sprung over the rim of the funnel body until the ring of said guard firmly rests upon the top edge of said funnel body. When the guard is in this position, its ring bridges the notches 23 and overlies the terminals 32 of the drinking cup arms.

By turning the catch 28 until the nose 28c projects over the ring 45, the guard will be tem-

porarily held in place and this will prevent the removal of the cup until said guard is released.

From the foregoing it will be apparent that I have provided a relatively compact poultry drinking fountain that may be quickly assembled and easily installed. While in use it provides a constant supply of fresh drinking water that cannot be contaminated under ordinary circumstances. If the nozzle is inverted, by unscrewing said nozzle one-half of a turn on its pipe 35, the water in the drinking cup functions as a trap to prevent air entering the lead-in branch should the water pressure be low and an outlet be opened ahead of the fountain. Also, with the nozzle inverted, a sufficient flow of water may be turned on to flush the drinking cup.

Of course I do not wish to be limited to the exact details of construction herein shown and described as these may be varied within the scope of the appended claims without departing from the spirit of my invention.

Having described my invention what I claim as new and useful is:

1. A poultry drinking fountain comprising a funnel including a bowl shaped body having an annular upper edge and a tapered exterior surface and a restricted neck, the latter adapted to be inserted in a drain pipe having a vertical portion providing an upper edge, a number of sets of concentric annular segmental ribs on the exterior of the funnel body, one set of which is adapted to engage the upper edge of the drain pipe, said body having a number of notches in its upper edge, a drinking cup, radial arms projecting from said cup and having terminal ends in a plane above the upper edge of said cup and resting in the notches, a nozzle pipe projected through a hole in the funnel body with its inner end extending to approximately the center of said cup, a nozzle on the inner end of the nozzle pipe, a guard resting on the upper edge of the funnel body and overlying the terminal ends of the cup arms to assist in holding them in place, and means to temporarily fasten the guard on the funnel body.

2. In a poultry drinking fountain, a funnel including a bowl shaped body having an annular upper edge and a reduced neck; a drinking cup suspended within said body; means to supply water to said cup; a lug projecting from the upper edge of the body; a catch pivoted to the lug; and a guard mounted on top of the body comprising a ring to rest on the upper edge of the body and be engaged by the catch, and a plurality of substantially vertical rods fixed in spaced relation about the ring above and below said ring and the upper portions converging to an apex, the lower ends of said rods extending below the ring and slightly inwardly below the ring to engage beneath the bowl shaped body.

WILLIAM L. LIPMAN.
